UNITED STATES PATENT OFFICE.

KENNETH G. CURRIER, OF EAST ORANGE, NEW JERSEY, AND JULES HEINRICH, OF NEW YORK, N. Y., ASSIGNORS TO FRED BUTTERFIELD & CO. INC., OF NEW YORK, N. Y., A CORPORATION OF NEW YORK.

DESIGN FOR FLOCKED VOILE FABRIC.

Application filed February 10, 1928. Serial No. 25,348. Term of patent 3½ years.

To all whom it may concern:

Be it known that we, KENNETH G. CURRIER and JULES HEINRICH, citizens of the United States, residing, respectively, in East Orange, county of Essex, State of New Jersey, and in the borough of Manhattan, city, county, and State of New York, have jointly invented a new, original, and ornamental Design for Flocked Voile Fabric, of which the following is a specification, reference being

had to the accompanying drawing, forming part hereof.

The figure is a plan view of a piece of flocke voile fabric showing our new design.

We claim:

The ornamental design for flocke voile fabric, as shown.

KENNETH G. CURRIER.
JULES HEINRICH.
